SEWING-MACHINE ATTACHMENT

John P. Enos, Union, N. J., assignor to The Singer Manufacturing Company, Elizabeth, N. J., a corporation of New Jersey

Application July 10, 1942, Serial No. 450,394

3 Claims. (Cl. 112—143)

This invention relates to sewing machine devices which are adapted to facilitate the production of felled seams.

To produce the usual type of felled seam in which two plies of material are involved, it is the usual practice to first superpose the edge portions of the two pieces of work and stitch them together a suitable distance from the edges of the work. The second and final operation is accomplished by opening the seam and inserting the free edges of the work in a regular presser-foot hemmer, thereby to complete the fell which is seamed by means of stitches passing through five plies of the work.

My U. S. Patent No. 2,296,509, dated Sept. 22, 1942, discloses a presser-foot hemmer of the type above referred to.

However, when it is attempted to secure two heavy or stiff pieces of work together by means of the above described felled seam, or to secure an edge portion of a single ply of material to the edge portions of two superposed plies of material by the same method, difficulty is experienced in properly loading the plies of fabric into the usual hemmer-foot. This difficulty arises because, in either of the two above cited cases, the plies are too stiff or heavy to bend readily about the hemmer-arbor. Therefore, if the various plies do not properly bend about the hemmer-arbor, the work cannot enter the required distance into the hemmer and consequently a defective seam will result. It is to obviate this difficulty that the present devices have been provided.

The present invention, therefore, has for an object to provide improved devices that will facilitate the proper formation of a felled seam, particularly when the work to be seamed comprises more than two plies or is composed of stiff and heavy materials.

The invention both in structure and in operation, as well as additional objects thereof, will be best understood from the following description taken in conjunction with the accompanying drawing, in which:

Fig. 1 is a perspective view of a hemmer-foot used in conjunction with the present invention as applied to a sewing machine.

Fig. 2 is a top-plan view of the hemmer-foot and the throat-plate embodying the invention.

Fig. 3 is a front view of the throat-plate shown in Fig. 2 and illustrating the action of the invention.

Fig. 4 is a section of the throat-plate taken substantially along line 4—4 of Fig. 2.

Fig. 5 is a fragmentary bottom plan view of the throat-plate embodying the present invention.

Fig. 6 is a section of a piece of work taken transversely of the line of seam formation.

In the drawing, the hemmer foot is shown as comprising a base-member or sole-plate 10 terminating in a shank 11 attached by the thumbscrew 12 to the usual presser-bar 13 of a sewing machine having a throat-plate 14 and a reciprocatory needle-bar 15 carrying the threaded needle 15'. The sole-plate 10 at its forward end is bifurcated to provide the spaced toes 16 and 17 and is apertured, as at 18, to provide the usual needle-hole.

Carried by the toe 17 is the usual hemmer scroll 19 having a leading work-folding edge 20 which extends spirally rearwardly between the toes 16 and 17 toward the needle-hole 18. The work-folding edge 20 is preferably steeply spiraled so that it will have a decided folding action on the marginal portion of the fabric as the same contacts the work-folding edge in its passage through the hemmer.

Carried by the toe 16 is a shank 21 having a conical-shaped arbor 22, the free end of which is disposed within the scroll 19 and directed toward the needle-hole 18. From Fig. 1 it will be seen that the marginal portion of the fabric is folded about the conical-shaped arbor 22 by the hemmer scroll 19. The arbor 22 and the sidewall 17' of the toe 17 form a cloth passageway through which the work is loaded into the hemmer-foot.

It is understood that the fabric is fed under the hemmer-foot by the usual feeding element or dog (not shown) common to sewing machines.

The above described hemmer-foot is adapted to operate in its usual manner but, according to the present invention, it is supplemented by a loading fin of spring wire resiliently supported on the sewing machine throat-plate 14. The throat-plate is of the usual type with the exception that it is provided with a narrow slot 23 disposed longitudinally of the direction of seam formation and in front of the hemmer-foot so as to be aligned with the fabric entrance thereof. The forward end 24 of the resilient wire is secured, by means of a screw 25, in a groove 26 formed in the bottom face of the throat-plate 14. The wire extends from this mooring upwardly through the slot 23 to form a work-engaging portion or fin 27 which is inclined upwardly toward the entrance of the hemmer-foot. As may be best seen in Fig. 2, this work-

engaging portion of the wire is disposed substantially parallel to the line of seam formation, and further, it is located to one side of the needle-hole 18, and is aligned with and extends into the cloth passageway as defined by the side-wall 17' and the arbor 22. The free end of the wire then extends downwardly through the slot 23 and is bent at right angles to the fin 27, thereby to form an arm 28. The screw 25 is preferably set upon the wire portion 24 so that the fin 27 is spring biased upwardly away from the upper surface of the throat-plate and so that the arm 28 will engage the bottom of the throat-plate 14 in order to prevent the free end of the wire from being raised above the throat-plate 14.

This throat-plate 14 is provided with the usual feed-dog slots 29 and a needle-hole 30 which is aligned with the hemmer-foot needle-hole 18. Fig. 5 shows that the slot 23 and the fin 27 are located to one side of the needle-hole 30 and that they are disposed in parallel relation with the feed-dog slots 29.

As may be best seen in Fig. 3, the fin 27 is adapted to engage the under face of the partially finished seam and force the upwardly projecting free edges 31 of the upper side of the work 32 into the hemmer-foot, thereby to cause the heavy three plies of material to enter the hemmer-foot the proper distance so as to insure that a perfect fell will be formed. As the fin 27 is resilient it will adapt itself for materials of different thicknesses.

Furthermore, the operator may control, with the aid of the present invention, the amount of material which is fed into the hemmer-foot. The operator need only place one hand upon each side of the work adjacent to the upwardly projecting free edges 31, and then by a spreading action of the hands downwardly and in opposite sidewise directions the free edges 31 are forced downwardly against the resilient fin 27 to a greater or less degree, thereby to limit the amount of material which the fin 27 may crowd into the hemmer-foot. It is particularly advantageous to be thus able to control the amount of material which may be fed into the hemmer-foot when the thickness of the work or the number of plies of the work varies during a single continuous seaming operation.

It is to be understood that the fin 27 may be adjusted transversely of the line of seam formation by loosening the screw 25 and shifting the wire portion 24 lengthwise within the slot 26. Furthermore, by turning the wire portion 24

within the slot 26, the normal height of the fin 27 may be adjusted to suit the various types of sewing conditions. By tightening the screw 25 upon the wire portion 24 the normal position 5 of the fin 27 becomes fixed. The fin is constructed of wire having sufficient strength to insure that the work is properly loaded into the hemmer. Of course, fins of various strengths may be used depending on the divers characteristics of the work to be seamed. The fin as herein illustrated is constructed of piano wire having a diameter of .025 inch. This fin was found to be particularly well adapted for use with silk and rayon materials.

15 Having thus set forth the nature of the invention, what I claim herein is:

1. A sewing machine throat-plate having a needle-hole and a slot, a spring wire of which one end is secured to the bottom surface of said 20 throat-plate, said wire having its body portion extending upwardly through said slot and normally disposed above the top surface of said throat-plate, the other end of said wire extending downwardly through said slot and being bent 25 at an angle to said body portion to underlie said throat-plate, and means to adjustably secure said wire to said throat-plate so that the wire may be adjusted transversely of said slot.

2. The combination with a hemming device 30 having a needle hole, an arbor and a side-wall, said arbor and said side wall forming therebetween a cloth passageway, of a cloth-plate opposed to said hemming device, a member carried by said cloth-plate and having a portion thereof 35 spring biased toward said hemming device, said member being aligned with said passageway and being effective to engage a portion of a cloth piece and force the same into said passageway to insure that a complete hem is made in said cloth 40 piece, and means to adjust said member transversely of said passageway.

3. The combination with a hemming device 45 having a sole-plate formed with spaced toes, a hemmer scroll carried by a first one of said toes, and a hemmer arbor carried by the second one of said toes, said hemmer arbor and said first toe forming therebetween a passageway, of a throat-plate opposed to said hemming device, and a fin carried by said throat-plate and aligned with 50 said passageway, said fin being adapted to engage a portion of the work and to force the same into said passageway.

JOHN P. ENOS.
